PROCEDURE AND APPARATUS FOR METAL
DRAWING

Wallace E. Kerr, Youngstown, Ohio

Application June 27, 1945, Serial No. 601,871

10 Claims. (Cl. 205—3)

1

This invention relates primarily to procedure and apparatus to be employed in metal drawing operations.

An object of this invention is to provide a driving connection between a constant-speed source of power and a variable-load driven apparatus, which is capable of being so adjusted that the power delivered to the driven apparatus is substantially proportional to the nominal load encountered by that apparatus and even though the source of power is a constant speed mechanism, such as a synchronous electric motor.

A further object is to provide a propelling mechanism for a variable load apparatus such that power may be delivered to such variable load apparatus so as to avoid peaking the power input factor to the apparatus.

A further object is to provide a driving mechanism for a sprocket and chain drive of, for example, a drawbench, which may be so adjusted that the variable speed condition occasioned by the sprocket and chain drive is appreciably diminished.

A further object is to provide control means for a variable power delivery mechanism, such as a fluid drive, which causes the controlled parts of such mechanism to respond successively to two control devices, one of which is rendered effective as the other is rendered ineffective.

A further object of the invention is to provide an improved driving connection between a source of power, such for example as a constant speed motor, and a device subjected to various loads, such for example as a drawbench, which may be quickly controlled to effectively vary the rate of application of the available power to the load in such a way as to minimize shock at the instant of initiating the application of such power to the load.

A further object is to provide simple and effective driving mechanism for the grip carrying device of a drawbench which includes a constant speed motor, such as a synchronous electric motor, as the source of power and which is so arranged that the speed of the draw may be varied, within limits, and so that the draw may be so initiated as to substantially eliminate shock and then rapidly accelerated.

A further object is to provide a structure including a drawbench in which the motive power for the drawing operation is delivered through the agency of a fluid drive and in which means are employed for controlling the operation of the fluid drive by the movement of the carriage along the carriage ways of the drawbench.

2

A further object is to provide an operating mechanism for a drawbench which includes a fluid drive and in which control mechanisms of the bench are employed for controlling the operation of the fluid drive.

An object of the invention is to provide a variable speed transmission mechanism for the grip carrying device of a drawbench in which the source of power is a synchronous electric motor and in which control means are employed for adjusting such mechanism in anticipation of the load and at a timed interval prior to the imposition of the load so as to avoid undue shock at the imposition of the load and for thereafter so increasing the power applied to the load as to rapidly accelerate such grip carrying device as it moves under load.

A further object is to provide a control mechanism for a fluid drive such that the scoop tube of the drive is so applied to the liquid annulus of the drive as to substantially avoid decreasing the effectiveness of the annulus by creating undue turbulence and frothing therein and which occasions a predetermined submergence of the scoop end of the tube within the annulus and then maintains the degree of such submergence substantially constant under the changing condition of the annulus occasioned by the removal of liquid therefrom as a result of such submergence.

These and other objects are attained by means of apparatus embodying the features herein illustrated and described and by means of procedure such as is herein defined.

In the drawings, accompanying and forming a part of my application,

Figure 1 is a diagrammatic, fragmental, side elevation of a unitary structure constituting my invention and involving a drawbench and a drive mechanism therefor.

Figure 2 is a top plan view of a portion of the apparatus illustrated in Figure 1.

Figure 3 is an elevation of a portion of apparatus shown in Figures 1 and 2 and a portion of such apparatus is shown in section along the line 3—3 of Figure 2.

Figure 4 is a sectional elevation of a hydraulic coupling or fluid drive (parts being omitted for convenience of illustration), the section being taken along the line 4—4 of Figure 2.

Figure 5 is a diagrammatic side elevation of a portion of the apparatus illustrated in Figure 4.

Figure 6 is a fragmental, sectional view along the line 6—6 of Figure 3, diagrammatically illustrating a detail of my invention. Parts of the apparatus illustrated are transposed for clarity.

Figure 7 is a sectional elevation of a pressure control valve constituting a detail of my invention.

Figure 8 is a sectional elevation of an adjustable pressure reducing valve, such as may be employed in connection with apparatus embodying my invention.

Figure 9 is a piping diagram, such as may be employed with apparatus embodying my invention.

Figure 10 is a piping diagram, such as may be employed in connection with a modification of the apparatus diagrammatically illustrated in Figure 9.

Figures 11 and 12 are each wiring diagrams.

Figures 13 to 20 inclusive and Figure 25 diagrammatically illustrate solenoid actuated contact devices or switches which are employed as a part of the electrical equipment constituting a detail of my invention.

Figures 21 to 24 inclusive are diagrammatic illustrations of electrically actuated valves illustrated in Figure 10 together with their actuating mechanisms which constitute details of the electrical equipment diagrammatically illustrated in Figure 12.

Figure 26 is a diagrammatic illustration of a portion of a power transmitting chain and its driving sprocket.

Figure 27 is a curve which indicates the usual variations in power input to a drawbench during a draw.

Figure 28 is a similar curve indicating improved power input conditions occasioned by the use of apparatus embodying my invention.

As illustrated in Figure 1, a drawbench consists essentially of a frame, a carriage mounted on the frame, one or more drawing dies carried by the draw head or die stand of the frame, means for moving the carriage along the frame away from the die stand to accomplish a draw and means for moving it toward the stand as a preliminary to a draw.

In the apparatus illustrated in Figure 1, dies 16 are carried by an upwardly projecting portion or die stand 16a which is shown as a part of and located at one end of the frame of the drawbench. The dies 16 are positioned above the ways 17 along which a grip-carrying carriage 18 is adapted to move. A grip 19 is diagrammatically illustrated as carried by the carriage at a point above the ways 17 and so positioned that its gripping jaws are in alignment with the dies 16. During a drawing operation, one end of stock (bar or tube) to be drawn is inserted through the die 16 and its projecting end is gripped by the jaws of a grip 19. When so gripped, it is drawn through the die by a movement of the carriage away from the die. The die stand may be provided with one or more dies and the carriage is provided with a separate grip aligned with each such die and arranged to cooperate with it in the drawing of stock.

The carriage 18 is moved along the ways 17, throughout the drawing operation, by means of a sprocket chain 22 and is adapted to be operatively coupled to that chain by means of a hook 23, shown as pivotally secured to the carriage at a point approximately midway the ends thereof. The hook 23 is normally held in its upper position as illustrated in Figure 1 by a latch 25, also pivotally secured to the carriage, and spring actuated to move into latching engagement with the hook. As shown, the latch 25 is actuated to release the hook 23 by a rod 26. The rod is slid-

ingly mounted on the carriage 18, is adapted to engage the die stand 16a as the carriage moves toward and into contact with it, and is shifted, relatively to the carriage and longitudinally of itself, by such engagement and thereby actuates the latch 25 to release the hook. The release of the hook permits it to drop into contact with the moving chain 22 and, by engaging a link of that chain, to operatively couple the carriage to the chain.

The elevation of the pivot point of the hook 23 is such that, after the hook is in engagement with the chain 22 and the chain is placed under tension by the drawing operation, the chain and hook will rise to such a position that the hook is engaged by the latch and retained by it in elevated position. Under such conditions, the chain will be automatically released from the hook and drop away from it—thus breaking the operative connection between the carriage and the chain—when the tension on the chain ceases by reason of the stock leaving the die. The latch 25 will, however, retain the hook 23 in the elevated position, to which it was raised by the pull of the chain 22, until the latch 25 is actuated by the rod 26.

After the carriage is operatively disconnected from the chain, its next movement will be toward the die stand 16a. This is accomplished by the grip-return mechanism. As diagrammatically illustrated in Figure 1, the grip-return mechanism includes a motor driven sheave 30 on which a cable 31 is reeved. The cable passes over sheaves 32 and 33 located at opposite ends of the frame and the opposite ends of the cable are shown secured to an extension 24 of the carriage 18. The sheave 30 is so driven that it normally propels the carriage toward the stand 16a. It is also so driven that its driving mechanism slips under excess torque, with the result that the carriage automatically stops as it abuts the stand 16a, and is at least momentarily held against the stand 16a by the grip-return mechanism.

As indicated, the grip-return mechanism is operated independently of the draw chain 22, except that its operation, like the operation of the draw chain, is in part controlled by the movement of the carriage 18.

The draw chain 22 is operatively coupled to the runner 35 of a fluid drive 36 by means of a shaft 35'. The fluid drive mechanism is diagrammatically illustrated in Figures 4 and 5 and includes an impeller 37, mounted on a shaft 37', and located in co-operative relation with the runner 35. The runner and the impeller are enclosed by a casing 37a which is carried by the drive shaft 37' but is so arranged, with relation to the runner 35, that the runner is capable of turning freely of it and also of the impeller 37.

In the type of fluid drive illustrated, both the runner and the impeller are provided with radially extending vanes and the relationship is such that power is transmitted from the shaft 37' to the shaft 35' or from the impeller 37 to the runner 35 by means of liquid, which is delivered to the interior of the casing 37a. That is to say, the fluid coupling is rendered effective, as a power transmitting device, by the delivery of liquid (such as oil) to the chamber enclosed by runner 35 and impeller 37 and in which the vanes of both are located. This chamber is sometimes referred to herein as the power chamber. The degree of the coupling's effectiveness, as a power transmitting device, varies with the amount of liquid within the power chamber. The runner

35 and impeller 37 rotate at the same or substantially the same speed when the casing 37a is substantially full of power transmitting liquid (oil) and the coupling is then most effective as a power transmitting agent.

It is noted that the fluid drive illustrated is a well-known commercial type of fluid coupling and, for that reason, the minute structural details of the same are neither disclosed nor described. In the type illustrated, the operating or power transmitting liquid is delivered to the interior of the casing 37a by means of a scoop tube 38. As shown, the scoop tube is located within a rotating cover 39 which, in effect, constitutes a rotating reservoir for the operating liquid delivered by the tube to the power chamber enclosed by the impeller and the runner. The cover 39 is supported by the drive shaft 37' and consequently is rotated at the speed of rotation of that shaft and of the impeller 37, with the result that the liquid contained therein forms, under centrifugal force, a liquid annulus which is located within an annular recess 40, formed around and within the cover 39.

In Figure 5, the dot-dash circumference of a circle illustrates the extent of the liquid annulus under conditions such as obtain while all of the power liquid is retained within the annulus. As shown by dotted lines in Figure 5, the scoop tube 38 is capable of being moved around its pivotal support to different positions so that its outer end or scoop is capable of occupying different positions with relation to the liquid annulus within the recess 40 of the cover 39. The scoop tube is there shown in three positions. One in which the scoop end of the tube is wholly removed from the liquid annulus; one in which the tube is so extended that the scoop end thereof projects into the annulus; and, one in which the tube is full extended and the scoop end thereof occupies a position adjacent the inner periphery face of the recess 40. Such movements of the scoop tube 38 are accomplished by a control lever 41.

As the scoop end of the tube 38 enters the moving liquid annulus, the liquid is forced, by its rotative movement, through the tube and communicating passages and into the power chamber enclosed by the impeller 37 and runner 35 and in which the vanes of both are located. As previously noted, the effectiveness of the fluid coupling depends upon the amount of liquid within the power chamber and, in the scoop tube control type of fluid coupling, the amount of liquid delivered to that chamber is controlled by the position of the scoop end of the tube with relation to the annulus of liquid within the recess 40 of the then rotating reservoir 39.

The casing 37a is provided with a series of leak-off ports 42, which are spaced around it and establish communication between the interior of that casing (i. e., the power chamber) and the interior of the reservoir 39. Under such conditions, liquid delivered from the reservoir 39 to the interior of the power chamber is continually leaking back into the reservoir, thus tending to empty the power chamber or casing 37a of liquid and to break the operative connection between the impeller 37 and the runner 35. It is for this reason that a continuous supply of liquid must be delivered to the casing 37a in order to render the coupling effective. The presence of the leak-off ports 42 also makes it apparent that the position of the scoop tube 38, with relation to the liquid annulus within the

cover 39, measures the effectiveness of the fluid coupling as a power transmitting mechanism. That is to say, the effectiveness of the coupling is controlled by moving the scoop end of the tube 38 to different positions with relation to the rotating liquid annulus.

The power liquid, which is stored in the form of an annulus within the rotating reservoir 39, is passed through a cooler during the cycle of its movement from one place to another. I, however, have not attempted to illustrate the cooler or the passages leading thereto and therefrom since commercial fluid couplings are usually equipped with coolers and other structural details which ensure their effective operation.

The shaft 37' may be operatively coupled to any prime mover, such as an electric motor, a steam engine, a turbine, or internal combustion engine. In the present embodiment, the use of 10 the fluid coupling makes it possible to employ a constant speed prime mover, such as a synchronous electric motor, as the source of power for the drawbench, i. e., the power source for actuating the draw head of the bench during 20 drawing operations. The shaft 35' is operatively coupled to the driving sprocket 45 of the draw chain 22. The shaft 37' is shown in Figure 2 as operatively connected to a synchronous electric motor 46.

In the apparatus illustrated, a drawing operation is initiated by a manually actuated control 30 and the further operations are then capable of being carried forward automatically. Assuming that a draw has been completed, that the carriage 18 occupies a position along the ways 35 17 remote from the die stand 16a and that the drawn stock has been removed from the grips and from the machine, the next step is to prepare for another draw. Under conditions assumed, the initiation of the drawing operation 40 will start the carriage 18 moving toward the die stand 16a. This is accomplished by grip-return mechanism and the arrangement is such that the carriage first moves at a relatively high speed toward the die stand 16a and, after it reaches a predetermined or selected point in its 45 return travel, its speed is checked so that it then moves slowly to its final position adjacent the stand 16a where the grips engage the stock to be drawn.

The starting of the grip-return mechanism is accomplished by means of a manually actuated control and, in the apparatus illustrated, the control is a push button forming a part of 55 an electrical control system. The initial return speed of the grip-return mechanism is reduced by a limit switch A, which is carried by the frame of the drawbench and is preferably adjustable to different positions along the line of travel of the carriage 18. The control device A is adapted to be actuated by an extension or cam secured to the carriage and so positioned that it is also capable of actuating a second limit switch or control device B also carried by the 60 frame of the bench and also preferably adjustable to different positions along the path of travel of the carriage 18. The extension or cam for actuating the control devices A and B may be indicated by the extension 24 to which the ends of 65 the grip-return cable 31 are shown secured. This extension will be hereafter referred to as the cam 24.

The first control device A checks the speed of the grip-return mechanism by means of apparatus, not here illustrated and forming no part

of the present invention, except that it does accomplish a checking of the speed of the grip-return mechanism. The second control device B also exercises a controlling function on the operation of the grip-return mechanism but, here again, the instrumentalities for accomplishing this are not illustrated. These control devices A and B are, however, important to the present invention because they co-operate with other mechanisms in accomplishing an automatic control of the drawbench and of the fluid coupling 36, which motivates the draw chain 22 and constitutes the effective source of power during the drawing operation.

In the apparatus illustrated, the impeller 37 of the fluid coupling is driven continuously by means of the motor 46, although the draw chain 22 is only driven during and immediately preceding a draw. The operation of the draw chain is controlled by the scoop tube 33 and, consequently, the automatic positioning of the scoop tube and the mechanisms for accomplishing such positioning form an important part of my invention.

In accordance with my invention, the fluid coupling 36 is so controlled that the draw chain is accelerated to what may be termed "hook-in" speed, i. e., a speed at which the carriage 18 can be effectively coupled to the chain without subjecting the apparatus to undue shock or impact strains but, at the same time, a speed which is sufficient to initiate the drawing operation. The draw may be initiated as the speed of the chain 22 is accelerating to draw speed and the acceleration may then be continued throughout the draw or until the desired draw speed is attained.

The completion of the draw and the resultant lessening of the load on the draw chain 22 not only breaks the connection between the chain and the carriage 18, by releasing the chain from the hook 23, but it also occasions an automatic withdrawal of the scoop tube 33 from the liquid annulus within the rotating reservoir 39 and thus renders the fluid coupling 26 ineffective by breaking the driving connection between the impeller 37 and the runner 35, i. e., by breaking the operating connection between the drive shaft 37' and the driven shaft 35'.

Apparatus is illustrated in Figure 10 which, in co-operation with other devices, accomplishes a rapid extension of the scoop tube 33 in the operation of partially filling the power chamber within the casing 37a as a preliminary to initiating a drawing operation. By employing the apparatus there illustrated, the fully withdrawn scoop tube may be rapidly moved to an extended position under the control of one device and at a rate which, if continued, would rapidly extend the tube to its extreme position. The operation of the apparatus is, however, such that during this rapid movement of the tube in response to the control of one device, the control is shifted to another device with the result that the second device positions the tube, with relation to the liquid annulus within the rotating covers 39, and thus designates the degree of effectiveness of the fluid coupling as a power transmitting device by controlling the extent to which the power chamber within the casing 37a is filled with liquid. The second device designates the position of the scoop tube and independently of the position to which it has moved when the second device becomes effective as the control device. Simultaneously with the initiation of the rapid move-

ment of the scoop tube, under the control of one device, the second control device is set for subsequently controlling the positioning of the tube. This second device, if acting alone, would occasion a slower movement of the scoop tube and a movement to some selected point of extension only, with the result that the power chamber of the casing 37a would be much more slowly filled, to the selected degree, with power transmitting liquid. Prior to the time that the scoop tube is totally extended, the instrumentality then controlling its movement is rendered ineffective with the result that the tube responds to the control of the second device.

The control lever 41 of the scoop tube is actuated by a motor 47 which is diagrammatically illustrated in Figures 3, 6, 9 and 10. As illustrated, the motor 47 is a diaphragm motor, is provided with a power-actuated lever 48 and is associated with a pilot valve mechanism, structural details of which are diagrammatically illustrated in Figure 6. The motor 47 is provided with a casing 49" which constitutes a support for a diaphragm 49 and a housing for a coiled spring 51 and a diaphragm-actuated link 52, which is pivotally connected to the lever 48. As shown in Figures 3 and 6, the cover 49' of the casing engages the edge of the diaphragm and with the diaphragm provides a pressure chamber 47a to which fluid pressure is delivered for the purpose of actuating the diaphragm. In the illustrated embodiment, the cover is provided with two ports 50' and 50a, each of which opens into the chamber 47a. The port 50' communicates with piping 53 and the port 50a communicates with a short length of pipe 54. The piping 54 communicates with a manifold 55 to which fluid under pressure is adapted to be delivered through piping 57' and which is provided with a supply port 57 controlled by a valve 58, located within the manifold and capable of being actuated by a beam 59.

The apparatus illustrated in Figure 6 is a diagrammatic simplification of a commercial type of pilot control mechanism for controlling the position of the diaphragm 49, and consequently the position of the lever 48, in response to the pressure of the fluid delivered to the manifold 55 through the piping 57'. As illustrated in Figure 6, the beam 59 approximates a walking beam and is supported by links 60 and 61. The link 60 engages and is supported by the diaphragm 49 and the link 61 engages and is supported by a pressure responsive device 62 illustrated as a form of sylphon bellows. Each of the links 60 and 61 is pivotally secured to the beam 59 and the bellows 62 is located within a pressure chamber 62a of the manifold 55 and is so arranged that its exterior is exposed to the pressure existing within that chamber, whereas its interior is open to the atmosphere. Under such conditions, one end of the beam 59 will move up and down in response to the variations in pressure delivered to the chamber 62a, whereas the other end will move with the diaphragm 49.

A coiled spring 59' is shown as operating between the beam 59 and the casing of the manifold 55 so as to tend to move the beam downward against such lifting force as may be applied thereto by either or both of the links 60-61. The spring 64 contributes to the opening of the supply valve 58 as either or both of the links 60 and 61 move upwardly.

The link 60 projects through the port 50a, the pipe 54, the passage 63 and a gasket 55'. The

passage 63 is formed within the manifold, with its lower end in open communication with the port 50a and its upper end communicating with a passage 63' also shown as formed within the manifold and adapted to communicate with the port 57 when the supply valve 58 is open. Thus the supply port 57 delivers fluid under pressure to the chamber 47a through the port 50a of the diaphragm motor 47 when the supply valve 58 is open. The supply valve is normally seated but an upward movement of the beam 59, acting through the coiled spring 64 and valve stem 58' raises it and thus places the supply port 57 in communication with passage 63' and delivers fluid under pressure to the chamber 47a.

Exhausting the fluid from above the chamber 47a causes the spring 51 to raise the diaphragm 49 and, consequently, the link 60 and one end of the beam 59, and, depending on the position of the link 61, will open the supply valve 58. That is to say, the supply valve responds to the relative positions of the two ends of the beam 59 or the relative positions of the diaphragm 49 and the bellows 62. Under such conditions, the diaphragm 49 will occupy a definite and predetermined position for each different fluid pressure delivered to, and maintained within the chamber 62a of the manifold 55.

The piping 53 is shown in Figure 10 as communicating with a source of fluid pressure, such as an adjustable pressure regulator valve 53', which is of more or less usual construction and is diagrammatically illustrated in Figure 8. The pipe 56 constitutes a branch pipe and extends between the chamber 62a of the manifold 55 and the pipe 53. It communicates with the pipe 53 at a point such that the inlet end thereof is in open communication with the source of regulated pressure, i. e., with the delivery port of the pressure regulator valve 53'. This pipe 56 includes a three-way valve V1, a three-way valve V2 and a pressure adjusting device 65, known commercially as a "grad-U-switch" (see Minneapolis Honeywell Regulator Company Bulletin, Bulletin 95-984A).

As illustrated in Figure 10, one position of the valve V1 establishes communication between the chamber 62a of the manifold 55 and an exhaust pipe 66. The valve is, however, capable of being turned so as to shut off communication with the exhaust pipe 66 and to establish communication with the valve V2 so as to place the delivery port of the device 65 in communication with the chamber 62a of the manifold 55. The valve V2 is shown in Figure 10 as establishing communication between the piping 56 and branch piping 67. The branch piping 67 also communicates with the piping 53 at a point such as to receive the fluid pressure delivered by the pressure regulator 53' and it is also provided with a pressure adjusting device 65' similar to the "grad-U-switch" 65. The device 65', like the device 65, is capable of being adjusted to deliver and maintain a predetermined pressure below that of the source of fluid pressure. The device 65 is in all respects similar to the device 65' and is diagrammatically illustrated in detail in Figure 7.

As shown in Figure 7, fluid is delivered to the interior chamber of the device 65 by what may be termed an inlet valve 68 which is normally seated by a coiled spring and the pressure of the fluid at the inlet port of the device and which is controlled by a pressure responsive diaphragm 69 through the agency of a stem 69a and lever 69'. The device is also provided with a discharge valve 68' which is normally held to its seat by a coiled spring and which responds to the movement of the diaphragm 69, being actuated by stem 69a and a lever 69". The diaphragm 69 is exposed on one side to the fluid pressure within the device and on the other side to atmospheric pressure and the pressure of an adjustable spring 70. The spring 70 is provided with an adjustable spring seat and this is positioned by means of a cam 71 capable of being turned to different positions by a hand lever 71', illustrated in Figure 10.

The piping 53 (Fig. 10) is interrupted by a valve V3 and communicates with an exhaust pipe 73 which is provided with a valve V4. The valve V3 is intermediate the source of pressure (pressure regulator 53') and the exhaust pipe 73 and is adapted to close off communication between the source of pressure and the pressure chamber of the diaphragm motor 47 when turned to the position indicated in Figure 10. When turned a quarter turn from that position, it establishes communication between the source of pressure and the diaphragm motor. The valve V4 is adapted to be turned to either establish or close off communication between the piping 53 and the exhaust pipe 73. In the position indicated in Figure 10, the exhaust pipe is, in effect, closed. A quarter turn of the valve V4 will, however, establish communication between the pipe 53 and the exhaust pipe 73 and exhaust the pressure from the chamber above the diaphragm 49 of the motor 47.

The valve V2 is adapted to establish communication between the chamber 62a of the manifold 55 and the delivery port of one or the other of the devices 65 and 65'. In the position indicated in Figure 10, it establishes communication between the chamber 62a and the device 65' (assuming the valve V1 is turned a quarter turn counter-clockwise) but by being turned a quarter turn counter-clockwise, communication between the device 65' is cut off and communication is established between the device 65 and the chamber 62a in which the bellows 62 are located.

As shown in Figure 6, the manifold 55 is provided with a small leak-off port 75 which communicates with the passage 63' and consequently with the pressure chamber 47a above the diaphragm 49 of the motor 47. This leak-off port is shown as a passage surrounding the stem 58' of the supply valve 58 and communicating with the passages 63' at a point immediately above the disk of the valve 58. With such an arrangement, fluid under pressure can only be maintained in the pressure chamber 47a while that chamber is in communication with a source of high pressure fluid, either through the port 50' or the port 50a as illustrated in Figure 6.

It will be apparent from Figure 10 that the valve V3, when open, delivers fluid under pressure direct from the pressure regulator 53' to the chamber 47a of motor 47 and causes the diaphragm 49, and the mechanisms actuated by it, to move in response to the pressure so delivered. It will also be apparent that a positioning of the valve V4, to place the piping 53 in communication with the exhaust pipe 73, will exhaust the pressure chamber 47a (if the valve V3 is closed). The passages and ports directly communicating with the valves V3 and V4 may be so proportioned that the opening of the valve V3 occasions a relatively rapid delivery of fluid under pressure to the chamber 47a and an opening of the valve V4 causes a rapid exhausting of that chamber. It will also be apparent that opening either of the valves V3 or V4 (the other being closed) will have

the effect of taking the control of the diaphragm motor 47 away from the pilot mechanism, i.e., the mechanism which includes the piping 56, the valves V1 and V2, the grad-U-switches 65 and 65' and the chamber 62a of the manifold 55. It will also be apparent that the valve V2 may be turned to render either the pressure adjusting device 65 or 65' effective, in controlling the positioning of the diaphragm 49, when the valve V1 is positioned to close the exhaust port 66 and both the valves V3 and V4 are closed. Likewise a shifting of the valve V1 to place the chamber 62a of the manifold 55 in communication with the exhaust pipe 66 will render both devices 65 and 65' ineffective as control mechanisms for the motor 47.

From the foregoing, it will be apparent that the apparatus diagrammatically illustrated in Figure 10 may be employed in controlling the positioning of the scoop tube 38 and that it may be so employed as to move and hold the tube in any one of four selected positions, viz., a position in which the tube is wholly withdrawn from the liquid annulus; one in which the tube responds to the control of the device 65' and the scoop end thereof is partially submerged by the liquid annulus; one in which the tube responds to the control of the device 65, is further extended and occupies a position, with relation to the annulus, such as will maintain an amount of liquid within the power chamber of the casing 37a essential for drawing operations; and, one in which the tube is fully extended.

When the valves V1, V2, V3 and V4 are all in the positions shown in Figure 10, the scoop tube will occupy the first mentioned position because the chamber 62a is open to the atmosphere through valve V1 and pipe 66 and the upper face of the diaphragm 49 is subjected to atmospheric pressure, the leak-off port 75 being open and all fluid delivery valves being closed. Under such conditions, the link 60 is moved to its uppermost position by the diaphragm 49 and the link 61 is moved to its lowermost position by the bellows 62 and the beam 59 occupies a position in which the supply valve 58 is closed.

Now assume that the device 65' is adjusted to deliver fluid from the source 53' at a relatively low pressure and the valve V1 is given a quarter turn counter-clockwise. Under such conditions, the bellows 62, responding to the fluid pressure so delivered to the chamber 62a, will partially contract, lifting the link 61 and moving the beam 59 about its pivotal connection with link 60. This will open the supply valve 58 and thereby deliver fluid under pressure from the source 53' to the chamber 47a above the diaphragm 49. The diaphragm, moving downwardly, in response to the pressure so delivered, will shift the position of the beam 59 around its pivotal connection with the link 61 and will close the valve 58 after reaching a predetermined position. Thus, it is apparent that the position of the diaphragm 49, at which the valve 58 is closed, will depend upon the position of the link 61 or the degree of fluid pressure acting on the bellows 62. In other words, the diaphragm 49 will move downwardly until the supply valve closes and this movement will move the tube 38 to the second position.

If it is now assumed that the device 65 is adjusted to supply fluid from the source 53' at a somewhat higher pressure than it is supplied from the device 65' and that the valve V2 is turned a quarter turn counter-clockwise, then, the chamber 62a will be subjected to the pressure

5 of the fluid delivered by the device 65. The bellows 62, responding to the increasing pressure, will raise the link 61 thereby lifting the beam 59 around its point of connection with the link 60 and will open the supply valve 58. Fluid under pressure will then be delivered by the supply valve 58 to the chamber 47a and that valve will remain open until the diaphragm 49, moving in response to the pressure within the chamber 47a, again shifts the position of the beam 59 sufficiently to close it. This movement of the diaphragm will move the tube 38 to the third of its above mentioned positions. If the lever 71' is turned counter-clockwise to its extreme position, the pressure delivered to chamber 62a would be such as to move the tube to the fully extended or fourth of the above mentioned positions.

In view of the fact that the leak-off port 75 (Fig. 6) is continually open, it will be apparent that, as soon as the diaphragm 49 moves to a position such that the valve 58 closes, its further movement will be arrested and the leaking-off of fluid from the chamber 47a will cause it to momentarily lift and open the valve 58, thus occasioning a momentary downward movement of the diaphragm and a closing of the supply valve. In other words, the diaphragm will "hunt" (pulsate) but will generally maintain the position designated by the position of the link 61 or the degree of fluid pressure delivered to the chamber 62a.

The fourth or fully extended position of the scoop tube 38 can also be attained by opening the valve V3 and maintaining it open a sufficient time to enable the diaphragm 49 to move to its lowermost position. As will be disclosed by the further description of the apparatus, the tube 38 may never fully extend while responding to the automatic operation of the apparatus illustrated, although its final position will always depend on the forces acting on the diaphragm 49 of the motor 47. It, however, should be noted that the device 65 may be so adjusted as to either partially or fully extend the scoop tube 38 during automatic operation and, therefore, during a draw.

A reference to Figure 3 will disclose that the power lever 48 is operatively connected to the scoop tube actuating lever 41 by means of link 76, lever 77, shaft 78, lever 79 and link 80. The power lever 48, the actuating lever 41 and the other parts of the motion multiplying mechanism are shown in full lines in the positions such that the scoop tube 38 is fully withdrawn from the liquid annulus or occupies the first above mentioned position. A stop 81 is carried by the frame of the apparatus and, by engaging the lever 79, limits the throw of the power lever 48 and thus designates the position occupied by that lever when the scoop tube 38 is fully extended or occupies the fourth of the above mentioned positions. The power lever 48, the lever 41 and the intermediate parts of the motion multiplying mechanism are shown in the extreme position by the dot-dash lines of Figure 3.

The arrow of Figure 5 designates the direction 65 of rotation of the cover 39 and, consequently, the direction of movement of the liquid annulus. The liquid of the annulus, therefore, resists extension of the scoop tube and on being penetrated tends to move the tube out of contact with it. The resistance offered by the liquid is substantial because the cover 39 is rotating at a relatively high speed. The resistance to penetration by the scoop tube also increases as the degree of penetration increases. On the other hand, the quantity of liquid in the annulus decreases as

the scoop tube transfers liquid therefrom to the power chamber within the casing 37a (Figure 4) of the fluid coupling. The resulting change in the liquid annulus contributes to the extension of the scoop tube, although the resistance to penetration by the tube does not decrease.

The effectiveness of the fluid coupling, as a power transmitting device, increases as the power chamber fills with liquid from the annulus. It is, therefore, desirable to fill the power chamber rapidly in order to conserve time in connection with the operation of the apparatus to which the power is transmitted by the coupling. On the other hand, it is desirable to so actuate the scoop tube that it penetrates the annulus without destroying its effectiveness by creating undue turbulence therein and a resulting frothing of the liquid. For this reason, the actuating fluid is delivered to the pressure chamber 47a above the diaphragm 49 (Figure 6) at a pressure which will cause the scoop tube to penetrate the annulus as rapidly as possible without destroying the effectiveness of the annulus. I also shift the control from one device to another, as described in connection with Figures 10 and 12, in order to speed the drawing operations of the drawbench.

As to this control, it will be noted that more rapid extension of the scoop tube will be accomplished in response to actuating fluid delivered directly to the chamber 47a through the piping 53 than is capable of being accomplished by delivering the actuating fluid through the piping 57', the supply valve 58 and the manifold connections, in response to the control of one or the other of the devices 65 or 65', although in each case the scoop end of the tube is applied to the liquid annulus under substantially the same conditions. The reason for the difference in the rate of tube extension is that the fluid pressure, delivered to the chamber 47a directly through the piping 53, is fully effective in moving the diaphragm 49 (and, consequently, in extending the scoop tube) up until the closing of the valve V3, whereas the movement of the diaphragm 49, occasioned by the delivery of actuating fluid through the supply valve 58, results in a gradual closing of the supply valve as the diaphragm 49 approaches the position designated by the then effective control device (65 or 65'). I, therefore, prefer to rapidly extend the scoop tube, and to over-extend it, by delivering actuating fluid through the piping 53 directly to the chamber 47a and then to position the tube under the control of one or the other of the devices 65' or 65, after the valve V3 is closed.

In the further description of the operation of the scoop tube, it should be borne in mind that an appreciable time (approximately 10 seconds) is consumed in filling the power chamber of the fluid coupling to the extent essential for accomplishing a draw at the desired rate. As to this, it will be recalled that the discharge or leak-off ports 42 of the power chamber (Figure 4) are continually open and that, therefore, a balanced condition is obtained as between the amount of liquid in the annulus and the extent to which the power chamber of the coupling is filled by holding the scoop tube in a fixed extended position and that, the degree to which the power chamber is filled and, consequently, the degree of effectiveness of the fluid coupling as a power transmitting device, will be varied by varying the position of the scoop tube with relation to the annulus.

It will also be noted that, under conditions described in connection with Figures 10 and 12, the force involved in accomplishing an extension of the tube 38 also accomplishes a predetermined submergence of the scoop end of the tube in the liquid of the annulus and then maintains that degree of submergence substantially constant as the extension of the tube continues in response to the changing condition within the annulus occasioned by the removal of liquid therefrom by the scoop tube in its function of delivering liquid to the power chamber.

In Figure 12, I have shown a wiring diagram which diagrammatically illustrates an electrical system employed for controlling the operation of the drawbench throughout the entire cycle of initiating and completing a draw. For the purpose of simplifying the wiring diagram, certain of the devices indicated in the diagram are more fully, although diagrammatically, illustrated in Figures 21 to 24 inclusive of the drawings. As to these figures, it is noted that Figures 21, 22, 23 and 24 are respectively diagrammatic illustrations of the valves V1, V2, V3 and V4, each being shown in connection with a diagrammatic illustration of its actuating devices. Throughout that portion of the description which bears on the wiring diagram of Figure 12, reference will be made to the appropriate figures (Figures 21 to 24) so as to amplify the disclosure of the wiring diagram.

Assume that a draw has been completed; that the carriage 18 is remote from the die stand 16a; and, that it is desired to start the cycle of the drawbench for the purpose of initiating and completing a further drawing operation. This is accomplished by momentarily depressing the grip-return switch, shown in Figure 12 as a push button type of switch C, so as to break the connection between leads x7 and x8 and establish electrical connection between leads x13 and x14, thus completing the circuit X, x13, switch C, x14, x15, solenoid D', x16, x17, contact Ea, forming a part of the contact device E, x18 and Y.

It should be noted that the motor M, which is the driving motor 46 operatively connected to drive shaft 37' of the coupling 36, is operating under minimum or idling load conditions and that the minimum load input of current traverses the circuit X, x1, motor M, x2, solenoid H' of the contact device H, x3 and Y but is not sufficient to energize the solenoid H' to operate the contact device H. Energizing the solenoid D' actuates the contact device D and moves the contact Da to establish the circuit X, x26, contact Ba of the switch device B, x21, contact Da, x28, x29, x21, x15, solenoid D', x16, x17, contact Ea of the contact device E, x18 and Y, thus establishing a holding circuit for the solenoid D'. Momentarily depressing the switch C (grip-return switch) also starts the operating motor of the grip-return mechanism and under conditions such that it moves the carriage 18 at full speed toward the die stand 16a. The circuit for accomplishing this is not shown, forming no part of the present invention. This full speed movement of the carriage 18 continues until the cam 24 depresses the contact device A (Fig. 1), which not only reduces the speed of the grip-return motor and consequently of the carriage 18 but also establishes the circuit X, x26, Ba, x27, Da, x28, x29, x22, contact Aa, x23, x24, solenoid F' of the contact device F, x25, x17, Ea, x18 and Y.

Energizing the solenoid F' breaks electrical contact between the wires x53 and x54, prevent-

ing the solenoid $V2'$ being energized, and also renders contact Fa effective thus establishing the circuit X , $x26$, contact Ba , $x27$, contact Da , $x28$, $x30$, contact Fa , $x31$, $x44$, $x47$, $x48$, solenoid $V3'$, $x49$, contact Ga of time relay device G (Fig. 20), $x50$ and Y , thus causing the valve $V3$ to move a quarter turn counter-clockwise from the position shown in Figure 10 and deliver fluid pressure to the diaphragm motor 47 through the piping 52 and direct from the pressure source (pressure regulator $53'$). This, in turn, actuates the lever 48 and under conditions such that the scoop tube 33 moves at a maximum rate and tends to completely fill the power chamber $37a$ of the fluid coupling 36 .

Closing the contact Fa also establishes the circuit X , $x26$, contact Ba , $x27$, contact Da , $x28$, $x30$, contact Fa , $x31$, $x33$, solenoid $V1'$, $x34$ and Y , thus causing the valve $V1$ to move a quarter turn counter-clockwise from the position shown in Figure 10 and, in that way, place the chamber $62a$ in communication with the device $65'$ through the valve $V2$, the valve $V1$, the branch piping 50 . This causes the bellows 62 to move in response to the pressure delivered by device $65'$ and to position the link 61 in what has been termed the second selected position. This sets apparatus so that fluid pressure, as adjusted by the device $65'$, will be effective in controlling the position of the lever 48 and, consequently, the scoop tube 33 after the valve $V3$ is closed. It should be noted that the carriage 18 is still moving toward the die stand $16a$, that the hook 23 is held out of contact with the draw chain 22 by the latch 25 , and that consequently moving the scoop tube 33 to render the fluid coupling 36 operative merely causes the chain 22 to move but without being subjected to a drawing load.

Rendering the contact Fa effective establishes the circuit X , $x26$, contact Ba , $x27$, contact Da , $x28$, $x30$, contact Fa , $x31$, $x44$, $x45$, solenoid G' of the time relay device G , $x46$ and Y . Energizing the solenoid G' will, after a brief time interval, move contact Ga of the time relay G and break the electrical connection between $x49$ and $x50$ thereby opening the energizing circuit of solenoid $V3'$.

The delayed action of the solenoid G' is occasioned by the dashpot mechanism Gp which is diagrammatically illustrated in Figure 12 and which delays the action of the solenoid G' for a definite period (a few seconds) after the solenoid is energized. De-energizing the solenoid $V3'$ results in an immediate closing of the valve $V3$ and this places the control of the diaphragm motor 47 on the device $65'$, the valve $V1$ being turned a quarter turn counter-clockwise from the position shown in Figure 10. As previously pointed out, the pressure chamber above the diaphragm 49 of the motor 47 , is always in communication with a leak-off port 15 consequently the excess pressure, delivered through the valve $V3$, is dissipated and the diaphragm 49 , therefore, responds to the pressure of the fluid delivered through the supply valve 57 and the passages of the manifold 55 after the valve $V3$ is closed. That is to say, if the scoop tube 33 has been over-extended it will move back as the diaphragm 49 (Fig. 6) adjusts its position to correspond to the pressure delivered by the device $65'$.

The carriage 18 is continuing its movement toward the die stand $16a$, although at a slow speed, and the cam 24 depresses the switch mechanism B . This actuates contact Ba to break electrical contact between the wires $x26$ and $x27$.

and renders the contact Bb effective in establishing the circuit X , $x35$, contact Bb , $x36$, $x37$, solenoid E' , $x38$ and Y thus energizing the solenoid E' and actuating the device E to break electrical connection between the wires $x17$ and $x18$ and render the contact Eb effective. The breaking of the circuit by opening the contact Ba , de-energizes the solenoids D' , F' , $V1'$ and G' . The closing of contact Bb establishes the circuit X , $x35$, Bb , $x36$, $x41$, $x42$, contact Eb , $x43$, $x47$, $x48$, solenoid $V3$, $x49$, contact Ga , $x50$ and Y . The energizing of the solenoid $V3'$ again opens the valve $V3$ delivering maximum fluid pressure to the motor 47 and thus tending to over extend the scoop tube 38 .

Closing the contact Eb also establishes the circuit X , $x35$, Bb , $x36$, $x41$, $x42$, contact Eb , $x43$, $x44$, $x33$, solenoid $V1'$, $x34$ and Y . Energizing the solenoid $V1'$ turns the valve $V1$ a quarter turn counter-clockwise from the position shown in Figure 10. Closing the contact Eb also simultaneously establishes the circuit X , $x35$, Bb , $x36$, $x41$, $x42$, contact Eb , $x43$, $x47$, $x51$, $x52$, solenoid $V2'$ (Fig. 22), $x53$, contact Fb , $x54$, and Y . (Note that contact Fb , Figure 17, is normally closed unless solenoid F' is energized.) Energizing the solenoid $V2'$ turns the valve $V2$ a quarter turn counter-clockwise from the position shown in Figure 10 which closes off communication between the device $65'$ and the manifold 55 and establishes communication between the device 65 and the manifold, the valve $V1$ being open or in a position to close off communication with the exhaust pipe 66 . The valves $V1$ and $V2$ are, therefore, so positioned that the motor 47 will respond to the pressure delivered by the device 65 as soon as the time relay G acts to de-energize the solenoid $V3'$ by breaking electrical contact between wires $x49$ and $x50$.

Rendering the contact Eb effective also establishes the circuit X , $x35$, Bb , $x36$, $x41$, $x42$, contact Eb , $x43$, $x45$, solenoid G' , $x46$ and Y . Energizing the solenoid G' causes the time relay to operate and break the electrical connection between wires $x49$ and $x50$, after a brief time interval, thus de-energizing solenoid $V3'$ and shutting off the delivery of fluid through the piping 53 to the diaphragm motor 47 . This shifts the control of that motor 47 to the device 65 through the valves $V1$ and $V2$, the branch piping 56 and the manifold 55 . Thus, the scoop tube is extended in response to fluid pressure delivered direct to the pressure chamber $47a$ through piping 53 , and then its position is adjusted under the control of the device 65 , which, in fact, designates the position of the diaphragm 49 at which the supply valve 57 (Fig. 6) closes.

When all this has occurred the carriage 18 has moved slowly into engagement with the die stand $16a$ and the rod 26 has moved to release the hook 23 so that it drops into engagement with the chain 22 and operatively couples the carriage 18 to the chain. The grips 19 , carried by the carriage, have also engaged and gripped the stock projecting through the dies 16 as a preliminary to initiating a draw. The draw starts slowly because at the time the hook 23 engages the chain 22 , the fluid coupling is not highly effective as a power transmitting device. As the liquid content within the power chamber of the coupling increases, the effectiveness of the coupling increases, with the result that the coupling, acting through the chain 22 and carriage 18 , initiates the draw at slow speed and then accelerates the movement of the carriage, so that the draw is

completed at a rate designated by the position assumed by the scoop tube 38 under the control of the device 65. The time lag, encountered in filling of the power chamber of the coupling to the desired extent contributes to the initiation of the draw at slow speed and, therefore, without undue shock or strain.

As the latch 25 is actuated to release the hook 23 and operatively connect the carriage 18 to the draw chain 22, the draw is initiated by the carriage moving away from the die stand 16a. As this movement continues, the cam 24 releases the contact B and current is shut off to the motor driving the grip-return sheave 30 by mechanisms not shown with the result that the drawing movement of the carriage 18 drives the grip-return motor in a reverse direction through the agency of the cable 31 and the sheave 30.

The load on the carriage increases the current input to the motor M which, as noted, is operatively connected to the drive shaft 37' of the fluid coupling 36. The increased current input to the motor M energizes the solenoid H' of the contact device H establishing the circuit X, x39, contact Ha, x40, x41, x37, solenoid E', x38 and Y thus establishing a holding circuit for the solenoid E' and so maintaining the circuit last described after cam 24 releases the switch mechanism B and causes the contact Bb to move out of electrical connection with wires x35 and x36. Energizing the solenoid H' also moves contact Hd to break the electric connection between x55 and x56 thus establishing a situation wherein the solenoid V4' (Fig. 24) cannot be energized until the last mentioned electrical connections are again established.

The energizing of solenoid H' also moves the contact Hd to establish the circuit X, x4, x5, contact Hd, x6, x11, solenoid I' of the contact device I, x12 and Y. Energizing the solenoid I' closes contact Ib. This, however, has no effect on the energizing circuit of solenoid V4' because contact Hd is open. The energizing of the solenoid I' also actuates the contact Ia to establish the circuit X, x4, x7, switch C, x8, switch L, x9, contact Ia, x10, x11, solenoid I', x12 and Y, thereby providing a holding circuit for the solenoid I'.

When the carriage 18 has moved away from the die stand 16a to a point such that the draw has been completed (the stock pulling out of the die), it and the motor M are immediately relieved of the drawing load with the result that the current input to the motor M immediately diminishes to the no load minimum and the solenoid H' is no longer effectively energized. This actuates the contacts Ha and Hd, interrupting the electrical connection between wires x5 and x6 and between wires x39 and x40. De-energizing solenoid H' causes contact Hd to establish the circuit X, x55, contact Hd, x56, contact Ib, x51, solenoid V4', x58 and Y. Opening the contact Ha shuts off the energizing current to the solenoids V1', E', G' and V2' which results in an opening of the contact Eb and a shifting of the valves V1 and V2 to the positions shown in Figure 10. This not only shuts off the supply of fluid pressure to the chamber 62a of the manifold but it also establishes communication between that chamber and the atmosphere through the pipe 56, the valve V1 and the pipe 66. As a result of this, the beam 59, moving in response to the equalizing of pressure on the interior and exterior of the bellows 62, occasions a closing of the supply valve 58 (Fig. 6) thus shutting off the supply of fluid pressure to the pressure chamber 47a above the dia-

50

phragm 49 of the motor 47. Energizing the solenoid V4' (Fig. 24) shifts the valve V4 a quarter turn from the position shown in Figure 10 thus establishing direct communication between the pressure chamber 47a and the exhaust pipe 73 through the medium of the pipe 53 and the valve V4. This accomplishes an immediate exhausting of the pressure chamber 47a. The solenoid V3' is not energized and consequently the valve V3 is closed.

As a result of all this, the diaphragm 49 (Fig. 6) moves to its uppermost position (in response to pressure of spring 51) and thereby totally retracts the scoop tube 38, i. e., withdraws it from the annulus of liquid within the rotating reservoir 39. This cuts off the supply of liquid to the casing 37a (Fig. 4) with the result that the leak-off ports 42 empty that casing and, therefore, are effective in breaking the operative connection between the impeller 37 and the runner 35 or the operative connection between the drive shaft 37' and the driven shaft 35'. That is to say, the driving connection between the motor M (46) and the draw chain 22 is broken with the result that the chain 22 ceases to move the carriage 18 and the motor M runs idle, i. e., under minimum load conditions. Unloading the chain 22 causes it to drop away from the hook 23 which, as previously noted, was moved into latching engagement with the latch 25 (Fig. 1) as the drawing load caused the chain to straighten out or rise and thus lift the hook 23 with it and into engagement with the latch.

With the various parts of the apparatus in the positions last described, a momentary closing of the push button switch C will break the circuit X, x4, x7, switch C, x8, switch L, x9, contact Ia, x10, x11, solenoid I', x12 and Y thus de-energizing solenoid I' and opening contact Ib, thereby de-energizing solenoid V4'. This will close the valve V4 or close off communication between the piping 53 and the exhaust pipe 73. The momentary depression of the switch C will also close a circuit (not shown) for delivering current to the driving motor of the grip-return mechanism and, therefore, will initiate a return movement of the carriage 18. The momentarily depressed button C will also establish the circuit X, x13, contact C, x14, x15, solenoid D', x16, x17, contact Ea, x18 and Y and thus initiate the cycle of the drawbench which has just been described.

The push button switch J, diagrammatically illustrated in Figure 12, may be termed the "draw reset switch." When depressed, it establishes the circuit X, x59, contact J, x60, x41, x37, solenoid E', x38 and Y. Energizing the solenoid E' initiates all the operational steps previously described as ensuing therefrom during the automatic operation of the drawbench while the hook 23 is in engagement with the chain 22 and the grips 9 are drawing stock through the dies 16. The switch J, therefore, provides manual means for initiating all automatic operations described as resulting from the automatic actuation of the control device B to render the contact Eb effective as a part of a current delivering circuit.

The switch K, shown in the form of a push button in the diagram of Figure 12, may be termed the "hook-in reset switch." Depressing the switch K closes the circuit X, x61, switch K, x62, x51, x47, x44, x32, x24, solenoid F', x25, x17, contact Ea, x18 and Y. Energizing the solenoid F' initiates the series of operations previously described as ensuing therefrom during

70
75

the automatic operation of the drawbench. The switch K, therefore, constitutes manual means for initiating the automatic operations which followed the cam actuation of the contact device A and the closing of the contact Aa.

The switch L may be termed the "grip-return jog switch" and a momentary depressing of that switch establishes the circuit X, x19, switch L, x20, x21, x15, solenoid D', x16, x17, contact Ea, x18 and Y. That is to say, the momentary depressing of the switch L will set up a situation, such as previously described; i. e., one which initiates a movement of the carriage 18 toward the die stand 16a, which movement continues only so long as the switch L is depressed.

In Figure 26, I have diagrammatically shown a portion of the draw chain 22 in association with a diagrammatic representation of the driving sprocket 45 fixed to the shaft 35', which is a portion of the transmission 35'. As there indicated, the effective radius of the driving sprocket varies from a maximum of R to a minimum radius r. Under ordinary conditions, the power input, from the sprocket 45 to the chain 22, varies directly as the length of the effective radius and, therefore, causes fluctuations of the current input to the motor M, such as may be represented by the wavy line S of Figure 27.

Comparison of Figures 27 and 28 will graphically illustrate an advantage gained by one feature of my invention. Each figure represents a power input curve, such as is traced by a recording wattmeter, where the motor involved is actuating the grip-carrying carriage of a drawbench. Figure 27 represents such a curve where the fluid coupling forming a part of the drive mechanism, is adjusted with relation to the amount of liquid in the power chamber, so as to insure the delivery of sufficient energy from the motor 46 to occasion an effective operation of the drawbench under the drawing conditions involved. In other words, the curve of Figure 27 illustrates power input during a draw, where the drive includes a fluid coupling in which the power chamber is overfilled for the imposed load. It also approximates a condition such as would be encountered where the sprocket 45 of the drawbench is connected to the operating motor by an ordinary or non-yielding form of mechanical coupling.

The curves of Figure 27 disclose that normally the power input peaks to a point T at the beginning of a draw, i. e., to a point considerably above the power input required to continue the draw after it is initiated and well under way. Even greater input peaks than illustrated by the curve S are encountered where mechanical or positive couplings are employed between the driving motor and the draw chain. Such peaks cause thrashing of the draw chain 22, particularly at the beginning of each draw, and tend to break the stock being drawn.

Irregular torque conditions, such as are indicated by the wavy portion of the line S are occasioned by the sprocket chain drive and are also objectionable. Here again, such conditions are accentuated where a positive coupling—instead of a fluid coupling—is employed.

I avoid the peaking at the beginning of the draw and the result of the irregular torque conditions during the draw, by so adjusting the device 65 that the extent or the degree to which the power chamber of the fluid coupling is filled, is such as to limit the power delivering capacity

such that a predetermined rate of draw cannot be exceeded. As a result the slip between the impeller 37 and runner 35 will increase for excess loads over the predetermined maximum and will decrease when the load is below the predetermined maximum. In other words, the rate of draw will vary as the load conditions vary and will vary in such a way as to maintain an approximately constant load on the prime mover (motor 46). The curve S' of Figure 28 indicates the power input under conditions described and it will be noted that the input peak, at the initiation of the draw, is avoided, and that the irregularity in the fluctuations of input, occasioned by the sprocket chain drive, are materially decreased. All this avoids shocks and undue strains and materially reduces the amount of scrap occasioned by breaking the stock during a draw.

In Figure 9, I have illustrated a somewhat modified arrangement of apparatus which may be employed for the purpose of controlling the operation of the fluid coupling 36. As there illustrated, the manifold 55 and communicating piping are dispensed with, with the result that actuating fluid for the diaphragm motor 47 is delivered directly to the pressure chamber 47a of that motor, from either the grad-U-switch 65 or 65'. Each such switch is similar in all respects to the corresponding device illustrated in Figures 7 and 10 and the intent is to so control them that the device 65 is effective in delivering fluid to the motor 47 at a higher pressure than that of the fluid so delivered by the device 65'.

As shown in Figure 9, the piping 56 corresponds to the piping 53 of Figure 10 and communicates with a source of fluid under pressure (such as pressure regulator 53') through pipe 53a. It also communicates directly with chamber 47a of motor 47. The device 65 intervenes between the pipe 53a and the piping 56 which, as in Figure 10, also includes the valves V1 and V2. The valve V1, in the position shown in Figure 9, establishes communication between the pressure chamber 47a of the motor 47 and an exhaust pipe 73' but is capable of being turned counter-clockwise to establish communication between its inlet port and the delivery port of the valve V2, while cutting off communication with the exhaust pipe 73'.

The valve V2 functions exactly as the valve V2 of Figure 10 and is capable of being turned counter-clockwise, from the position shown in Figure 9, thus cutting off communication between the device 65', and the valve V1 and establishing communication between that valve and the device 65 and, through valve V1 with the pressure chamber 47a of the motor 47. The device 65' is located in branch piping 67 which communicates with the source of high pressure fluid (pipe 53a) and, in effect, constitutes a by-pass around the device 65 when the valve V2 is in the position shown in Figure 9 and the valve V1 is turned a quarter turn, counter-clockwise, from the position shown in that figure.

In describing the operation of the apparatus illustrated in Figure 9, reference is made to the wiring diagram of Figure 11. As to the diagram of Figure 11, it is noted that many of the electrical devices, diagrammatically illustrated as a part thereof, are the same devices as are illustrated in Figures 14 to 22 inclusive and Figure 25. For that reason the reference characters employed in the wiring diagram of Figure 11 are similar to those

employed in the diagram of Figure 12, with this difference, the relationship between each numeral and letter, employed as a reference character is reversed. In the description of the apparatus of Figure 9, I have assumed that a draw has just been completed and that the carriage 18 is standing at a point along its ways remote from the draw stand 16a. Under such conditions, the motor M, which drives the sprocket 45 and the draw chain 22, is idling because the fluid coupling 36 is ineffective, i. e., is not transmitting power from the drive shaft 37' to the driven shaft 35'. However, the current input, requisite for the idling load, is passing from the line wire X through 1x, the motor M (46) 2x, the solenoid h' of the contact device h, 3x and Y, illustrated in the wiring diagram of Figure 11. The amount of current traversing this circuit, however, is not sufficient to energize the solenoid h' and actuate the contact device h, with the result that the contact Ha is in a position such that electrical contact is broken between the wires 39x and 40x. The carriage 18 is not only remote from the die stand 16a but the hook 23 is released from the draw chain 22 and is held in its uppermost position by the latch 25 (Figure 1).

With the parts in the relationship stated, the switch C (Figure 11) is momentarily depressed thereby completing the circuit X, 13x, switch C, 14x, 15x, solenoid D', 16x, 17x, contact Ea of the contact device E, 18x and Y. Closing the switch C has the same effect, in connection with the wiring diagram of Figure 11 and the apparatus of Figure 9, as previously described in connection with Figures 10 and 12. That is to say, it starts the grip-return mechanism so that the carriage 18 moves at full speed toward the die stand 16a.

Energizing the solenoid D' actuates the contact Da (Figure 19) and completes a holding circuit for the solenoid D' which circuit is as follows: X, 26x, contact Ba of switch device B, 27x, contact Da, 28x, 29x, 21x, 15x, solenoid D', 16x, 17x, contact Ea, 18x and Y. This holding circuit is maintained during the movement of the carriage 18 toward the die stand 16a and until the carriage is close to that stand. During this movement, the cam 24 engages and actuates the switch device A which, as previously noted, is adjustably mounted so that its position along the carriage way 17 may be varied. Actuating the switch A moves the contact Aa to complete the circuit X, 26x, contact Ba, 27x, contact Da, 28x, 29x, 22x, contact Aa, 23x, 24x, solenoid F', 25x, 17x, contact Ea, 18x and Y, thus energizing the solenoid F' of the contact device F, thereby establishing electrical contact between wires 30x and 31x and breaking electrical contact between wires 53x and 54x of Figure 11.

During this return movement of the carriage 18, the valves V1 and V2 are in the positions illustrated in Figure 9. That is to say, the valve V1 establishes communication between the piping 56' and the exhaust pipe 73' thus maintaining atmospheric pressure within the pressure chamber 47a above the diaphragm 49 of the diaphragm motor 47 (Figure 3) and the valve V2 is in the position to establish communication between the branch pipe 67' and the piping 56'.

Depressing the switch A also actuates devices not shown and thereby slows the movement of the carriage 18 toward the die stand 16a. Establishing the electrical contact between wires 30x and 31x completes the circuit X, 26x, contact Ba, 27x, contact Da, 28x, 30x, contact Fa, 31x, 32x, 24x, solenoid F', 25x, 17x, contact Ea,

18x and Y thereby maintaining the energization of the solenoid F'. The completing of the last mentioned circuit also energizes the solenoid V1' since wire 33x is electrically connected to wire 31x. Under these conditions, all three solenoids D', F', and V1' are energized. Energizing the solenoid V1' causes the valve V1 to move a quarter turn counter-clockwise and thus close off communication between piping 56' and the exhaust pipe 73' and, at the same time, establish communication between the piping 67' and 56' through the valve V2 which is in the position illustrated in Figure 9. This delivers fluid under pressure to the chamber 47a of the diaphragm motor 47 direct from the control device 65' and, consequently, actuates the diaphragm 49 (Figure 3) to extend the scoop tube at a rate and to a position designated by the pressure of the fluid so delivered to the chamber 47a. This occasions the delivery of liquid to the power chamber of the fluid coupling (Figure 4) and renders the coupling effective in driving the draw chain 22 but at a relatively slow speed. The hook 23 is, however, latched in its uppermost position and the carriage 18 therefore, continues to move toward the die stand.

During this movement, the cam 24 engages and depresses the switch mechanism B which, like the switch mechanism A, is adjustably mounted along the way 17 of the carriage 18. Depressing switch B simultaneously actuates both of the contacts Ba and Bb (Figure 16) so as to break the electrical connection between the wires 26x and 27x and to establish electrical connection between the wires 35x and 36x. This breaks the circuits supplying current to the solenoids D', F' and V1' but completes the circuit X, 35x, contact Bb, 36x, 37x, solenoid E, 38x and Y.

De-energizing the solenoid D' actuates the contact Da (Figure 19) to break electrical connection between the wires 27x and 28x; de-energizing the solenoid F' (Figure 17) breaks the electrical connection between the wires 30x and 31x but establishes electrical connection between wires 53x and 54x. Neither of these contacts, however, change the electrical situation because other contacts, with which they are associated, are open.

While breaking the circuit of the solenoid V1' de-energizes that solenoid and, therefore, moves or tends to move the valve V1 to the position to exhaust the pressure chamber 47a above the diaphragm 49, the results flowing from the energizing of the solenoid E' are so nearly simultaneous with the de-energizing of the solenoid V1' that the pressure chamber 47a is actually maintained under pressure. For example, energizing the solenoid E' actuates the contact mechanism E to break electrical contact between the wires 17x and 18x but to establish electrical contact between the wires 42x and 43x. This completes the circuit X, 35x, contact Bb, 36x, 41x, 42x, contact Eb, 43x, 52x, solenoid V2', 53x, contact Fb, 54x and Y. It also completes the circuit to the solenoid V1' since the wire 43x is electrically connected to the wire 33x by the wire 44x. It, therefore, follows that the solenoids V1', E' and V2' are all energized.

The carriage 18 is now contacting the die stand 16a with the result that the rod 26 has actuated the latch 25 to release the hook 23 and thereby couple the carriage to the draw chain 22 and the grips 19 have engaged and gripped the stock to be drawn. The energizing of the solenoids V1',

and $V2'$ has caused each of the valves $V1$ and $V2$ to turn a quarter turn counterclockwise from the positions shown in Figure 9 thus shutting off communication between the piping $56'$ and the exhaust $73'$ and also between piping $56'$ and the branch pipe $67'$. The turning of the valves $V1$ and $V2$ establishes communication between the pressure chamber $47a$ of the motor 47 (Figure 3) and the source of fluid pressure $53a$ through the device 65 , the valve $V2$, the valve $V1$ and the piping $56'$. This delivers fluid under pressure to the pressure chamber $47a$ and the pressure of the fluid so delivered is adjusted by the device 65 .

The pressure of the fluid delivered by the device 65 is preferably materially greater than that delivered by the device $65'$ with the result that the scoop tube is not only extended at a more rapid rate, in response to this increased pressure, but is also further extended with the result that, under the control of the device 65 , sufficient liquid will be delivered to the power chamber of the coupling to materially increase the effectiveness of the fluid coupling as a power transmitting device and to accomplish the draw at the desired rate of speed. It should, however, be noted that because of the time lag involved, the hook 23 engages the chain 22 as the power chamber of the coupling is filling to the extent designated by the control device 65 and, for that reason, the chain is still moving at a relatively slow speed. As soon as the coupling is capable of transmitting sufficient power to initiate the draw, the carriage 18 moves away from the die stand $16a$ in response to the pull of the chain 22 . This movement is initiated at a very slow speed, although the carriage accelerates to the full drawing speed as the power chamber fills to the extent designated by, and in response to the then position of the scoop tube.

As the tension on the chain 22 increases in response to the increasing effectiveness of the fluid coupling as a power transmitting device, it straightens out and, in the particular draw-bench illustrated, lifts the hook 23 into latching engagement with the latch 25 , thus locking the hook in its elevated position while it continues to function as the coupling between the chain 22 and the carriage 18 .

The load imposed on the motor M by the drawing operation increases the current input to that motor to the extent that the solenoid h' is energized sufficiently to actuate the contact device h and move the contact Ha into electrical engagement with the wires $39x$ and $40x$. This completes a holding circuit for the solenoids $V1'$, E' and $V2'$ and continues those circuits after the switch mechanism B is released by the cam 24 (as carriage 18 moves to the left) thus breaking the electrical connection between the wires $35x$ and $36x$. The movement of the switch mechanism B establishes the electrical connection between the wires $26x$ and $27x$, but this is ineffective in establishing an operating circuit because the contact Da is open, breaking electrical connection between the wires $21x$ and $28x$.

The carriage 18 continues its movement to the left until the draw is completed, at which time the motor M is relieved of the drawing load with a resultant decrease in the current input to the motor. This de-energizes the solenoid h' which results in a movement of the contact device H such that the contact Ha moves out of electrical connection with the wires $39x$ and $40x$. This breaks the holding circuit for the solenoids

$V1'$, E' and $V2'$ de-energizing the same with the result that each of the valves $V1$ and $V2$ is returned to the position, illustrated in Figure 9, and the contact Ea moves to again establish electrical contact between the wires $17x$ and $18x$. The contact Eb moves to break electrical contact between the wires $42x$ and $43x$ thus preventing re-establishing the last mentioned holding circuit. The completion of the draw relieves the chain 22 of the draw load and this permits it to drop away from or release itself from the hook 23 , which, as previously noted, is held in the raised position by the latch 25 .

With the mechanisms in the positions described, the only effective circuit is that including the motor M , (X , $1x$, motor M , $2x$, solenoid h' , $3x$ and Y) but, as noted, the current traversing that circuit is reduced to the amount necessary for operating the motor under minimum load conditions and as a result solenoid h' is ineffective.

Depressing the push button or draw reset switch J will, under such conditions, establish the circuit X , $59x$, switch J , $60x$, $41x$, $37x$, solenoid E' , $38x$ and Y which energizes the solenoid E' and, through the action of the contact device E , re-establishes the circuits for energizing the three solenoids $V1'$, E' , and $V2'$, and, therefore, the switch J may be employed as an emergency switch for re-establishing the adjustment of the mechanisms essential for operating the carriage under drawing load, and independently of the position of the carriage 18 along its way 17 .

It will also be understood that, after the completion of a draw and after all circuits have been opened, except the circuit supplying current to the motor M at minimum load input, depressing the push button C will initiate another drawing cycle by completing the circuit through the solenoid D' and through the contact Ea , which is closed under the conditions indicated. As previously noted, the depressing of the button C will deliver current (by instrumentalities not shown and forming no part of the present invention) to the motor actuating the grip-return mechanism with the result that the drawing cycle will be initiated by starting the carriage 18 to move at full speed toward the die head $16a$.

Depressing the push button or hook reset switch K establishes the circuit X , $64x$, switch K , $52x$, $44x$, $32x$, $24x$, solenoid F' , $25x$, $17x$, contact Ea , $18x$ and Y . Energizing the solenoid F' opens the contact Fb breaking the circuit for solenoid $V2'$ and closes the contact Fa thereby delivering current to solenoid D' through the wires $44x$, $31x$, contact Fa , $33x$, $29x$, $21x$, $15x$, solenoid D' , $16x$, $11x$, contact Ea , $18x$ and Y . It also establishes a current flow from the wire $44x$ through the wire $33x$, solenoid $V1'$, wire $34x$ and Y , thus energizing the solenoid $V1'$ and turning the valve $V1$ a quarter turn counterclockwise thus establishing communication between the device $65'$ and the pressure chamber of the motor 47 . Under such conditions, the scoop tube is moved by the motor 47 to a position such as to partially fill the power chamber $37a$ and, therefore, drive the chain 22 at a slow or hook-in speed.

The switch L has been termed the "grip-return jog switch." Its function is to interrupt other operative circuits for the purpose of moving the carriage 18 back toward the die head $16a$. When moved to the position which establishes electrical contact between wires $19x$ and $20x$, it establishes the circuit X , $19x$, switch L , $20x$, $21x$,

15x, solenoid D', 16x, 17x, contact Ea, 18x and Y. That is to say, the momentary depressing of switch L sets up a circuit through the solenoid D' of the contact device D—i. e., a circuit similar to one previously described—and initiates a return movement of the carriage toward the die stand 16a which movement continues so long as switch L is so depressed.

From the foregoing description, it is apparent that the apparatus, diagrammatically illustrated in each of Figures 9 and 10 constitutes a part of a system of co-operating instrumentalities which occasions the automatic initiation of the draw with a minimum of shock and at a rate such as avoids subjecting either the drawn stock or the drawing mechanisms to undue strains. Each such apparatus or system initiates the draw at a low rate of speed and then accelerates the drawing mechanism to the desired drawing speed. The apparatus of Figure 10 is effective in occasioning a more rapid acceleration of the carriage 18 than the apparatus of Figure 9, due to the fact that it occasions a rapid extension of the scoop tube under the control of one device and then shifts the control to another device which positions the tube and, therefore, designates the extent to which the power chamber of the coupling is filled with liquid from the annulus. In this way, the filling of the power chamber is accelerated and, as a result, the period of the operating cycle of the drawbench is shortened and the drawbench is, therefore, capable of doing more work in a designated period of time.

While I have illustrated two forms of apparatus for carrying out my invention and have described the procedures involved, it will be understood that various changes, additions, substitutions and omissions may be made in both the apparatus illustrated and the procedure defined without departing from the spirit and scope of my invention as defined by the appended claims.

What I claim is:

1. A method of operating a draw bench equipped with a die stand and a grip-carrying carriage movable toward and away from said stand, a chain for actuating said carriage during the drawing operation away from said stand and a sprocket for driving said chain, which consists in operatively coupling the carriage to said chain to accomplish a drawing operation while said chain is moving at a slow speed; then increasing the speed of said chain while so limiting the driving power applied to said sprocket that the rate of angular movement of said sprocket varies inversely with the variations in the effective driving radius of said sprocket, decreasing as the effective radius increases and increasing as the effective radius decreases.

2. A power-transmitting assembly including a constant speed motor; a driven mechanism, and a fluid coupling comprising a rotatable impeller operatively coupled to said motor, a rotatable runner operatively coupled to said driven mechanism, a power chamber formed within said impeller and runner, a reservoir casing secured to and rotatable with said impeller and a scoop tube operating within said casing to deliver power-transmitting liquid therefrom to said power chamber; and a control mechanism for extending said tube to different positions with relation to a liquid annulus formed in said casing during rotation thereof in combination with a device for controlling said control mechanism

to extend said tube at one rate toward a predetermined position with relation to such annulus; a separate device for controlling said control mechanism to extend said tube at a different rate to a different position with relation to such annulus; and means responsive to movement of said driven mechanism for shifting the control of said control mechanism from one of said devices to the other during the operation of said driven mechanism.

3. A power-transmitting assembly, comprising a driven mechanism movable in two directions, i. e., a forward movement under load and a return, load-free movement back to a load-receiving position; operating means for moving said mechanism during such return movement; a constant speed motor for impelling said mechanism during its forward movement; a fluid coupling between said motor and said mechanism for transmitting power to said mechanism and moving the same throughout such forward movement, said coupling comprising a rotatable impeller, operatively coupled to said motor, a runner operatively coupled to said mechanism, a power chamber enclosed by said impeller and said runner and means for delivering power-transmitting liquid to said power chamber and controllable to adjust the extent to which such chamber is filled with such liquid during rotation of said impeller; a control mechanism for rendering said liquid delivery means effective and for controlling the rate of delivery of liquid thereby to said power chamber; a device rendered effective during the return movement of said driven mechanism to control said control mechanism to actuate said liquid delivery means to deliver liquid to said power chamber at a predetermined rate; a second device rendered effective during the return movement of said driven mechanism to control said control mechanism to actuate said liquid delivery means to deliver liquid to said power chamber at a different predetermined rate; and means actuated by said driven mechanism during the return movement thereof for actuating said first mentioned device to control said mechanism and then to shift such control to said second device.

4. A power-transmitting assembly including a driven mechanism movable in two directions, i. e., a forward movement under load and a return, load-free movement back to a load-receiving position; means for moving said driven mechanism throughout said return movement; a constant speed motor for impelling said driven mechanism throughout such forward movement; a fluid coupling for transmitting power from said motor to said mechanism to thereby impell said mechanism throughout its forward movement, said coupling comprising a rotatable impeller operatively coupled to said motor, a rotatable runner operatively coupled to said driven mechanism, a power chamber formed within said impeller and said runner, and a reservoir casing rotatable with said impeller; a scoop tube operating within said casing to deliver power-transmitting liquid therefrom to said power chamber; a control mechanism for extending said tube to different positions with relation to a liquid annulus formed in said casing during rotation thereof; in combination with a device rendered effective during the return movement of said driven mechanism for controlling said control mechanism to extend said tube toward a predetermined, annulus-engaging position within said casing; a second device for controlling said con-

tral mechanism to position said scoop tube in a load-carrying position with relation to said annulus and means actuated by said driven mechanism during the return movement thereof for rendering said first mentioned device effective in controlling said control mechanism and for then rendering said second device effective for controlling said control mechanism and for shifting such control from said first mentioned device to said second mentioned device during the return movement of said mechanism.

5. A power-transmitting assembly including a driven mechanism movable in two directions, a forward movement under load and a return load-free movement back to a load-receiving position; means for moving said driven mechanism throughout said return movement; a constant speed motor for impelling said driven mechanism throughout such forward movement; a fluid coupling for transmitting power from said motor to said mechanism to thereby impell said mechanism throughout its forward movement; said coupling including a rotatable impeller operatively coupled to said motor, a rotatable runner operatively coupled to said driven mechanism, a power chamber formed within said impeller and said runner, a reservoir casing rotatable with said impeller and a scoop tube operating within said casing to deliver power-transmitting liquid therefrom to said power chamber; a control mechanism for extending said tube to different positions with relation to a liquid annulus formed in said casing during rotation thereof to thereby vary the liquid content within said power chamber; a control device for actuating said control mechanism to extend said tube at one rate toward a predetermined annulus-engaging position and to thereby deliver liquid to said power chamber at one rate of delivery; a second control device for actuating said control mechanism to position the extended tube to a load-carrying position with relation to said annulus to thereby deliver liquid to said power chamber at an adjusted rate; means actuated by said driven mechanism during the return movement thereof for rendering first one and then the other device effective in controlling said control mechanism.

6. A draw bench and its operating mechanism, comprising a die stand; a grip-carrying carriage movable toward and away from said stand; grip return means for moving said carriage toward said stand; carriage-actuating means for moving said carriage away from said stand throughout a drawing operation; a coupling device for operatively coupling said carriage to said carriage-actuating means; a driving motor for impelling said carriage-actuating means and said carriage throughout the movement thereof away from said stand; a fluid coupling between said motor and said actuating means for transmitting power from said motor to said actuating means, comprising a rotatable impeller operatively coupled to said motor, a rotatable runner operatively coupled to said actuating means, a power chamber formed by and within said impeller and said runner and liquid-delivery means for delivering power-transmitting liquid to said power chamber; a control mechanism for rendering said liquid delivery means effective; instrumentalities for actuating said control mechanism to render said liquid delivery means effective in delivering liquid to said power chamber while said carriage is moving toward said stand and in anticipation of the transmission of power from

said motor to said carriage; and means actuated by engagement with said stand while said carriage is moving toward the same for actuating said coupling device to couple said carriage to said carriage-actuating means while liquid is being delivered to said power chamber and the liquid content in said power chamber is increasing.

7. A draw bench and its operating mechanism, comprising a die stand; a grip-carrying carriage movable toward and away from said stand; grip return means for moving said carriage toward said stand; carriage-actuating means for moving said carriage throughout its movement away from said stand; a coupling device for operatively coupling said carriage to said carriage-actuating means; a motor for impelling said carriage-actuating means and said carriage throughout the movement of the carriage away from said stand; a fluid coupling between said motor and said actuating means for transmitting power from said motor to said actuating means and comprising a rotatable impeller operatively coupled to said motor, a rotatable runner operatively coupled to said carriage-actuating means, a power chamber formed by and within said impeller and said runner, a reservoir casing rotatable with said impeller and a scoop tube operating within said casing to deliver power-transmitting liquid therefrom to said power chamber; a control mechanism for extending said tube to different positions with relation to a liquid annulus formed within said casing during rotation thereof; a device for actuating said control mechanism during movement of said carriage toward said stand to extend said tube to a predetermined annulus-engaging position and to thereby deliver liquid from said casing to said power chamber at a predetermined rate; a second device for actuating said control mechanism to position the extended tube in a load-carrying position with relation to said annulus to thereby deliver liquid to said power chamber at an adjusted rate and predetermined the liquid content within the power chamber during movement of the carriage away from said stand; and means actuated by the movement of said carriage toward said stand for actuating said coupling device to couple said carriage to said carriage-actuating means to thereby move the carriage away from the stand while liquid is being delivered to said power chamber and the liquid content within said power chamber is increasing.

8. A draw bench and its actuating mechanism, comprising a die stand; a grip-carrying carriage movable toward and away from said stand; a chain for moving said carriage away from said stand during a drawing operation; a prime mover for driving said chain; a fluid coupling for transmitting power from said prime mover to said chain and consisting of a rotatable impeller operatively coupled to said prime mover, a rotatable runner operatively coupled to said chain and a power chamber formed by and within said impeller and said runner; a grip-return mechanism for moving said carriage toward said stand; liquid delivery means for delivering power-transmitting liquid to said chamber; a control mechanism for actuating said liquid-delivery means to deliver liquid to said power chamber and to vary the rate of liquid delivery to said chamber during movement of said carriage; instrumentalities rendered effective by said carriage as it moves toward said stand for actuating said control mechanism to control said liquid-delivery means to vary the rate of liquid delivery to said

power chamber during movement of said carriage toward said stand and to predetermine the extent to which such chamber is filled during the movement of said carriage away from said stand and a device actuated by said carriage as it moves toward said stand for coupling said carriage to said chain during the delivery of liquid to said power chamber and as the liquid content within said power chamber is increasing.

9. A draw bench and its actuating mechanism, comprising a die stand; a grip-carrying carriage movable toward and away from said stand; a carriage-actuating mechanism for moving said carriage away from said stand during a drawing operation; a constant speed motor for impelling said actuating mechanism; a fluid coupling for transmitting power from said prime mover to said actuating mechanism and consisting of a rotatable impeller operatively coupled to said motor, a rotatable runner operatively coupled to said actuating mechanism, a power chamber formed by and within said impeller, a rotatable reservoir casing operatively coupled to said impeller, and a scoop tube operating within said casing to deliver transmitting liquid therefrom to said power chamber; a grip-return mechanism for moving said carriage toward said stand; a control mechanism for extending said scoop tube to different positions with relation to a liquid annulus formed within said casing during the rotation thereof and for holding said tube in different predetermined, annulus-engaging positions during movement of said carriage; separate control devices for actuating said control mechanism to extend said scoop tube toward different predetermined annulus-engaging positions; means actuated by said carriage as it moves toward said stand for successively rendering said control devices effective in actuating said control mechanism to move said scoop tube to different annulus-engaging positions and to thereby deliver liquid at different rates of delivery to said power chamber during the movement of said carriage by said grip-return mechanism; a coupling device actuated by said carriage as it moves toward said stand to couple said carriage to said carriage-actuating means while said power chamber is receiving liquid from said reservoir chamber and while the liquid content within said power chamber is increasing.

10. A method of operating a draw bench, equipped with a die stand, a grip-carrying carriage movable toward and away from said stand, a chain for actuating said carriage in its move-

ment away from said stand during a drawing operation, a sprocket for driving said chain, a prime mover for driving said sprocket, and a fluid drive located between said prime mover and said sprocket for transmitting power from said prime mover to said sprocket, and consisting of a rotatable impeller operatively coupled to said prime mover, a rotatable runner operatively coupled to said sprocket, a power chamber formed by and located within said impeller and said runner, and means for delivering power-transmitting liquid to said power chamber at varying rates to adjust the liquid content within the power chamber during the rotation of said impeller; which consists in coupling the carriage to the chain while maintaining a low but increasing liquid content within the power chamber and consequently, while said chain is accelerating from a low speed, and then adjusting the liquid content within said power chamber to so limit the driving power applied to said sprocket by said fluid drive throughout the drawing operation, that the rate of angular movement of said sprocket varies inversely with variations in the effective driving radius of the sprocket, decreasing as the effective radius of the sprocket increases and increasing as the effective radius decreases.
